UNITED STATES PATENT OFFICE.

BRADFORD BORDEN, OF CLEVELAND, OHIO.

WORK HOLDER.

Application filed April 4, 1925. Serial No. 20,795.

My invention relates to work holders and particularly, although not necessarily, to a work holder and centering device for use in connection with die stocks.

5 Briefly stated, the paramount objects of the invention are to provide a work holding and centering device which may be quickly and accurately set by sight or touch for work of different sizes whereby it may be 10 efficaciously used in a dark or poorly lighted shop; to avail of a novel, variably positionable means for positively limiting advancement of the device toward the work, which means is designed to frictionally restrain 15 any tendency of the device to draw away from the work, means other than said retaining means serving to sustain the device; and generally to furnish a work holding and centering device which will be very 20 simple in its construction, strong and durable, and inexpensive of manufacture.

The foregoing and other features of novelty which characterize my invention are pointed out with particularity in the claims 25 annexed to and forming a part of this specification. For a better understanding of the invention, however, reference should be had to the accompanying drawings in connection with the following descriptive matter, the 30 drawings depicting what I now regard as a preferred embodiment of my inventive idea. It is to be understood, however, that I do not propose to limit myself to the exact construction shown in the drawings, and 35 that I am aware that various changes and modifications may be made without a departure from the invention as claimed.

In the drawings:—

40 Figure 1 is an elevation of a die stock illustrating the practical application of my work holder;

Figure 2 is a sectional view through the work holder, and

45 Figure 3 is a sectional detail depicting a slight modification.

Figure 4 is a perspective view of the adjustable stop employed in the modified form of the invention shown in Figure 4.

Referring specifically to the drawings, the 50 die stock which I have chosen to illustrate for showing the application of my work holder is denoted generally by the numeral 5, it being of the type disclosed in my co-pending application Serial 718,090 which 55 was filed on June 7, 1924. For present purposes it will suffice to say that the dies are

indicated at 5^a and that the stock is slidable on posts 6 which are fastened in a rotatable plate 7 carried by the neck 8^a of the body portion 8 of my improved work holder. In 60 operation the teeth of the dies 5^a bite into the work and cause movement of the die stock in the direction of the work holder.

The body portion of the work holder is shown as being cylindrical and is bored out 65 as indicated at 8^b co-axially with the opening in the die stock into which the dies 5^a project. The pipe or other work is presented to the dies through the work holder in the usual manner.

70 The member 8 has protruding from its outer periphery a plurality of radially arranged bosses 9 which are cored out as indicated at 9^a to form a bore which communicates through a relatively reduced tapped opening 9^b to the bore 8^b of the body portion.

75 The work engaging and centering members are designed to be received within the bosses 9, and such members include a relatively elongated screw threaded shank 10 80 formed integrally at its outer end with a cylindrical enlargement 11 having a plurality of circumferential grooves 12. The distance between each groove is proportional to the differences in the diameters of the 85 various standard sizes of work for which the device is adapted and it is to be noted that the wall of each groove, which is nearest the threaded shank 10, is beveled as indicated at 11^a, while the other wall is perpendicular to the axis of the cylindrical portion 11. A finger grip 13 is formed at the outer end of the cylindrical enlargement 11 whereby the shank 10 may be rotated to take in the threaded opening 9^b and to be 95 projected into the work receiving bore 8^b of the body portion. The diameter of the cylindrical portion 11 is such that it is slidably received in the bore 9^a of the boss 9.

100 Heretofore in using work engaging members characterized by screw threads, considerable difficulty has been experienced in securing an accurate setting of each of the plurality of members, it being obvious that in the absence of an accurate setting of each 105 member, the work will not be held in the exact center of the work receiving opening and exactly concentric to the opening into which the dies 5^a project. I have illustrated two means for accurately setting the work 110 holders for standard sized pipes or other work. In Figures 1 and 2 each of the bosses

9 is shown with a spring metal clip 14 which is held in place by means of screws 14^b and has its outer end turned downwardly as indicated at 14^a to flatly engage the end portion of the boss and to project slightly beyond the wall of the bore 9^a. If the largest standard sized work for which the holder is adapted is desired to be threaded, the work holder is screwed inwardly until the shank 10 properly engages the work in the opening 8^b. The end portion 14^a of the spring clip 14 slides along the periphery of the cylindrical portion 11 and when the end of the threaded shank 10 is properly engaged with the work as aforesaid, said end portion 14^a will drop into the groove 12 which is the nearest to the threaded shank 10. The finger grip 13 is then given the final twist which causes the straight rear wall of the groove 12 to bind against the outer face of the clip portion 14^a whereby the shank 10 is frictionally retained against accidental turning which would tend to destroy the adjustment and loosen the grip upon the work. It is obvious that the wall 11^b engaging the portion 14^a limits insertion of the shank 10. When it is desired to free the threaded work engaging shank 10 from the work, it is only necessary to manipulate the finger grip 13. The beveled wall 11^a of the groove 12 permits the end 14^a of the clip to slide out. It is to be noted, however, that the tension of the grip is strong enough to frictionally engage this wall to prevent the shank 10 from turning except upon actual manual manipulation of the finger grip 13.

In Figure 3 there is shown a modified form of the invention wherein a washer-like member 15 having an elongated opening 15^a is positionable upon the cylindrical portion 11 and is receivable in the grooves 12. The advantage of this form of the invention is that the washer 15 can be located in the desired groove 12 for a predetermined size of work before the shank 10 is tightened against the work. Upon manipulation of the finger grip 13 the washer 15 comes to bear against the end of the boss 9 which with the straight rear wall of the groove serves to positively limit further inward movement of the shank. A final twist of the finger grip 13 effects a binding of the washer 15 against the end of the boss and against the back wall of the groove. The shank 10 is thus frictionally held against the work as before.

From the foregoing it will be obvious that an accurate adjustment of the work holding shank 10 can be quickly made and once having been made will not be destroyed. If the shop where the tool is being used is poorly lighted, the workmen can readily locate either the end 14^a of the spring clip 14, or the washer 10, in the proper groove, by touch alone, since he will know the size

of the work and the relative location of the proper groove 12 for such size. During the threading operation the shanks 10 will be sustained by their threaded engagement with the openings 9^b. By use of the work holder 70 as described there will be no likelihood of the work being canted or positioned eccentrically in the opening or bore 8^b of the body portion 8.

Having thus described the invention 75 what is claimed is:—

1. The combination with a work holder comprising a body portion having a medial opening through which the work is adapted to be projected; of a plurality of radially extending bosses projecting outwardly from said body portion, said bosses having longitudinal bores therein and open at their outer ends, said bores communicating with the opening of said body portion through 85 relatively reduced tapped openings in the wall of said body portion, work engaging members threaded from one end thereof for the major portion of their lengths and having relatively enlarged cylindrical portions 90 extending throughout the balance of their lengths, the enlarged cylindrical portion of each of said work engaging members slidably fitting in the bore of one of said bosses, and the threaded portion of each of said members taking in said tapped openings and being adapted to be engaged with the work, said cylindrical portions having a plurality of spaced circumferential grooves formed 95 therein, the wall of each groove nearest the threaded portion of said member being beveled, and means selectively engageable in 100 said grooves whereby to limit the projection of said member against the work, and said means binding in said grooves and against the outer ends of said bosses upon rotation of said work engaging members 105 whereby to tend to prevent retraction thereof.

2. In a thread cutting tool, the combination with a work holder, including a work receiving sleeve; of a work centering device comprising radially adjustable screw threaded work engaging elements extending transversely of said sleeve and projecting therethrough, said work engaging elements having a plurality of accurately spaced abutments thereon, movable means selectively engageable with said abutments, and said movable means upon advancement of said 115 work engaging elements being brought to bear against the end of said sleeve whereby to limit further movement of said elements and by frictional engagement with the end of said sleeve and the abutments to restrain 120 the turning of said elements to retract the same from the work.

3. In a work holder for diesstocks and the like, a screw threaded boss, a screw working in said boss and having an unthreaded ex- 125 130

tension at the outer end thereof, the outer portion of the bore of said boss being unthreaded to slidingly receive said extension, a plurality of spaced abutments formed upon said extension, and movable means selectively engageable with said abutments, said means upon advancement of said screw being brought to bear against the end of said boss whereby to constitute a stop, and the binding of said means against said abutments and end of said boss serving to frictionally resist the turning of said screw to retract the same.

4. A work holder for thread cutting tools comprising a body portion having a medial work receiving opening, said body portion having a plurality of tapped radially extending openings communicating with said work receiving opening and relatively enlarged bores communicating with said tapped openings, work engaging members threaded throughout a portion of their length and taking in said tapped openings, the unthreaded portion of said members being enlarged to slidingly fit said relatively enlarged bores, and means variably positionable to engage the unthreaded portion of said members whereby to restrain the same against movement and whereby the said members may be accurately set to properly engage and center work of different sizes.

5. A work holder for thread cutting tools comprising a body portion having a medial work receiving opening, said body portion having a plurality of tapped radially extending openings communicating with said work receiving opening and relatively enlarged bores communicating with said tapped openings, work engaging members threaded throughout a portion of their length and taking in said tapped openings, the unthreaded portion of said members being enlarged to slidingly fit said relatively enlarged bores, said unthreaded portions having depressions cut therein, and means engageable in said depressions and adapted to abut against the body portion of said work holder when the work engaging members are advanced whereby to limit movement in the direction of the work, the abut-

ting of said members against said body portion effecting a binding thereof in said depressions whereby to restrain movement of said members as would disengage the same from set position against the work.

6. In a work holder for diestocks and the like, a tapped boss, a screw threaded member working in the tapped bore of said boss and having an unthreaded part at its outer end, the bore of said boss being unthreaded adjacent its outer end to receive the unthreaded portion of said member, the latter having a plurality of spaced circumferential grooves therein, movable means selectively engageable with said grooves and designed upon advancement of said member in said boss to engage the end thereof and act as a stop for said member, and the binding of said means against the outermost wall of a groove and against the end of the boss, serving to frictionally restrain said member against turning.

7. In a work holder, a tapped boss, a screw threaded member working in said boss and having a plurality of spaced circumferential grooves therein, means movable transversely of the axis of said member and selectively engageable in said grooves, said means upon engagement with the end of said boss constituting a stop for said member, and the binding of said means in said groove and against the end of the boss serving to frictionally restrain the member against turning.

8. In a work holder, a tapped boss, a screw threaded member working in said boss and having a plurality of spaced circumferential grooves therein, means carried by said boss and yieldingly movable transversely of the axis of said member and selectively engageable in said grooves, said means upon engagement with the end of said boss constituting a stop for said member and the binding of said means in said groove and against the end of the boss serving to frictionally restrain the member against turning, and the wall of each groove nearest said boss being beveled substantially as and for the purpose set forth.

In testimony whereof I affix my signature.
BRADFORD BORDEN.
